UNITED STATES PATENT OFFICE

ROY W. SCHWEIKER, OF LANSDALE, PENNSYLVANIA

LIGHTING FIXTURE

Application filed August 22, 1927. Serial No. 214,596.

This invention relates to lighting fixtures of that general class employing a plurality of sockets for electric bulbs or lamps.

In certain States, the requirement is made that in certain electric lighting installations, as, for instance, in hospitals, there shall be provided two independent electric lighting circuits, each having its own source of electrical energy, for instance, one circuit being the normal circuit, and another an emergency circuit, so that if the normal circuit becomes impaired the emergency or reserve circuit having its independent source of electrical current derived, for instance, from a storage battery, may be switched on.

The object of the present invention is to provide an improved lighting fixture particularly adapted for use in installations where the foregoing requirements must be observed, which will have separate electric sockets for separate lamps or bulbs, each socket being included in its own circuit independent of the remaining socket, and to relatively arrange the sockets and the electric lamps or bulbs carried by them so that under normal lighting conditions the bulb or lamp then used will cast no shadow on the glass shade which encloses the bulb; further, to arrange the emergency socket and bulb or lamp to provide adequate illumination when the emergency bulb is illuminated and the normally used bulb is unlighted.

The invention comprises a lighting fixture having, first, a pair of lamp sockets relatively arranged so that when the bulb normally used is illuminated, it will be so disposed within the enclosing glass shade that the rays of light will not be interfered with by reason of the remaining socket carrying the emergency unlighted bulb and, hence, no shadow will be cast on the shade, particularly in respect to rays which are directed downwardly because it will be understood that the invention is particularly designed for use on ceiling lighting fixtures; second,

a lighting fixture having a pair of lamp sockets respectively containing a high power, long-neck electric bulb for normal use and a low power short bulb for emergency use, the respective sockets being on independent circuits, one of which is supplied by the usual lighting circuit and the other by a storage battery of suitable, independent, auxiliary source of electric current.

In practice, the two sockets are arranged at an angle to each other both being carried by supporting means applied to, and preferably contained within, the lamp canopy, each socket being separately wired.

The embodiment of the invention which is hereinafter described and is shown in the accompanying drawings utilizes a type of canopy and supporting plate set forth in certain of my earlier applications and patents but it is not essential to the present invention that the latter be used in connection with this particular type of canopy and supporting plate when the invention is regarded in its broadest aspect.

In the accompanying drawings:

Figure 1 is a vertical section on the line 1—1, Figure 2, through the canopy and supporting plate, showing the invention, dotted lines representing the outline of the glass shade;

Figure 2 is a bottom view of the supporting plate and the sockets; and

Figure 3 is a similar view, the sockets being omitted.

The canopy appears at 1 and, as shown, is of the contour and characteristics of the porcelain canopies shown and described in certain of my earlier applications.

The metal strap shown at 2 constitutes a means for connecting the canopy to the electrical outlet box which is attached to the ceiling or wall of the room where the fixture is used.

The canopy 1 is supported by a plate 3 which is located under a shoulder 4 on the

canopy. The plate 3 is suspended from the strap 2 by any suitable number of bolts 5 which are screwed into the strap at 6, and whose lower ends pass through holes 7 in the plate 3 and are provided with supporting nuts 8 having a screw threaded engagement with the bolts 5.

As thus far described, the construction is generally the same as that shown in my earlier applications.

I provide two electric sockets 9 and 10 which may be of any suitable construction or type. These sockets are secured to the plate 3 by bosses 11, 12, carried by the sockets, and extending through openings 13, 14 in the plate 3, nuts 15, 16 being screwed on the bosses to clamp the sockets 9, 10 against the plate 3. It is not material how the sockets 9, 10 are fastened in position.

The socket 9 is arranged at an angle, other than 90°, in relation to the plate 3. The socket 10 may either be disposed at an angle of 90° to the plate 3 or at an inclination, it being understood that the relative disposition of the sockets 9 and 10 is such that when the normal or high powered electric bulb 17 is screwed into the socket 9, it will be disposed in the general central axis of the glass shade or globe shown by dot and dash lines 18^a and near to the lower part thereof so that by employing a high powered, long-necked bulb 17 for normal lighting purposes, and by employing a lower power short-necked bulb 18 in the socket 10 for emergency lighting purposes, the illumination normally provided by the bulb 17 is not interfered with, at least, as to rays of light projecting through the bottom or outermost side of the shade 18^a and no troublesome shadow is cast on the shade by reason of the employment of the emergency bulb 18.

The socket 9 is in the normal lighting circuit 19, whereas the socket 10 is included in the emergency lighting circuit 20 which receives its current from any suitable auxiliary, independent, source of power, as, for instance, from a storage battery.

Normally, the circuit 20 is open, any suitable switch being provided for that purpose; consequently the bulb 18 is only used in case of failure of the current supplied to the circuit 19. The bulb 17 is the one which is normally used for lighting purposes and receives its current from the usual lighting circuit in which are included the wires 19.

A practical embodiment whereby the socket 9 is arranged at an angle other than 90° to the plate 3, is that shown where the plate 3 is provided with a tilted or inclined offset or seat 21 so that the base of the socket 9 is received in said seat and hence the socket is disposed at an angle as shown. Should the current supplied to the circuit 19 fail, the lamp 18 can be illuminated by closing the circuit 20 and will afford adequate illumina-

tion during the emergency, although the lamp 17 will cast a shadow on the shade 18 in that instance.

In practice, while I do not limit the invention thereto, a 40 watt lamp may be used as the emergency lamp, whereas a 100 or 150 watt lamp may be used at 17.

What I claim is:

1. A lighting fixture provided with a fixture plate, an electric lamp socket carried thereby in offset relationship to the central part of said plate and which is inclined in relation to said fixture plate in a direction toward the general central axis of the fixture, a long-necked electrical lamp carried by said socket and having its bulb disposed in the general central axis of the lighting fixture and adapted for normal use, a second electric lamp socket carried by said fixture plate in offset relationship to the central part of said plate, and a short-necked electric lamp carried by said last-named socket and disposed above the bulb of the long-necked lamp and adapted for emergency use.

2. A lighting fixture comprising a canopy, a socket supporting plate engaged therewith which also supports the canopy, and independent electric lamp sockets carried by said plate, said sockets being relatively inclined in downwardly converging relation to each other for disposing the lamps carried thereby in downwardly converging relationship to each other, a short-necked lamp in one of said sockets, and a long-necked lamp in the other socket, whereby the bulb of the long-necked lamp is disposed in advance of the bulb of the short-necked lamp and lies in the general central axis of the fixture.

3. A lighting fixture provided with a fixture plate having an aperture in the central part thereof, an electric lamp socket carried by said plate in offset relationship to the central part of said plate and which is inclined in relation to said plate in a direction toward the general central axis of the fixture, a long-necked electric lamp carried by said socket and having its bulb disposed in the general central axis of the lighting fixture and adapted for normal use, circuit wires from said socket which run through the aforesaid aperture, a second electric lamp socket carried by said fixture plate in offset relationship to the central part of said plate, a short-necked electric lamp carried by the said last-named socket and disposed above the bulb and the long-necked lamp, and circuit wires independent of the aforesaid circuit wires, connected to said last-named socket and running through the aforesaid aperture.

4. A lighting fixture comprising a canopy, a fixture plate engaging and supporting said canopy, said plate having a seat which is inclined or offset in relation to the plane of the said plate, a lamp socket engaged with, and

connected to, said seat and, by virtue of its seating, being disposed in inclined relationship to the seat in a direction toward the central axis of the fixture, and another lamp socket connected to said plate, a long-necked electric lamp carried by said first-named socket, and a short-necked electric lamp carried by the last-named socket, the bulb of the long-necked electric lamp being below the bulb of the short-necked lamp.

10 In testimony whereof I hereunto affix my signature.

ROY W. SCHWEIKER.
